EXPANSIBLE MANDREL

Ernest E. Keyes, Kalamazoo, Mich., assignor of
one-half to Edward H. Edelman, Kalamazoo,
Mich.

Application January 8, 1938, Serial No. 184,009

11 Claims. (Cl. 242—72)

This invention relates to improvements in expandable mandrels.

The main objects of this invention are:

First, to provide an expandable mandrel for rolls of paper and the like which is highly effective in holding the roll of paper, avoiding the necessity for using cores, and permitting it to be completely unwound.

Second, to provide an expandable mandrel which is adapted to support rolls of paper without tearing or mutilating the same as the paper is wound up or unwound.

Third, to provide an expandable mandrel having these advantages which may be quickly and easily adjusted and locked in its adjusted positions.

Objects pertaining to details and economies of the invention will appear from the description to follow. The invention is defined in the claims.

20 A structure embodying the features of the invention is illustrated in the accompanying drawings, in which:

Fig. 1 is a fragmentary partially longitudinal section of an expandable mandrel embodying features of the invention, a roll of paper being indicated thereon.

Fig. 2 is a fragmentary transverse section on line 2—2 of Fig. 1, showing the clutch rollers in expanded position, adjusting tools or wrenches being shown in position for manipulating the mandrel.

Fig. 3 is a transverse section on line 3—3 of Fig. 1.

Fig. 4 is a fragmentary view illustrating the locking cams in locking position as distinguished from the position shown in Fig. 1 in which they are in their initial position.

Fig. 5 is a fragmentary view partially in longitudinal section on line 5—5 of Fig. 6 of a modified form or embodiment of my invention particularly desirable for larger diameter mandrels.

Fig. 6 is a fragmentary view partially in section and partially broken away on the line 6—6 of Fig. 7.

45 Fig. 7 is an enlarged fragmentary side view of the modification in Fig. 5.

Fig. 8 is a detail view mainly in section on line 8—8 of Fig. 7.

The embodiment of my invention illustrated in Figs. 1 to 4 inclusive comprises a shaft 1 having a plurality of peripheral cam surfaces 2 extending longitudinally thereof and adapted to receive and actuate the clutch rollers 3. These clutch rollers are preferably knurled as shown in the drawings. The shaft is surrounded by the

sleeve 4 having longitudinal slots 5 therein receiving the rollers 3. The cam surfaces 2 terminate in seats 6 at their inner ends of such depth that when the clutch rollers are engaged or rest in the seats their peripheries are substantially flush with the periphery of the sleeve 4 as is shown in Fig. 3. The cams are of substantial length so that the clutch rollers are gradually moved from the seats to clutching position as the shaft and sleeve are relatively rotated in mandrel expanding direction.

The sleeve is supported at one end by the thrust collar 7 pinned to the shaft at 8. At its opposite end the sleeve is provided with a helical cam surface 9 which is formed in the embodiment illustrated on the collar member 10 shouldered to receive the end of the sleeve and welded thereto as indicated at 11, see Fig. 1.

The shaft is provided with a thrust collar 12 which is secured to the shaft by the pin 13 and between this thrust collar 12 and the cam member 10 is a clamping collar 14 having a cam surface 15 opposed to the cam surface 9 on the sleeve. The clamping collar 14, the thrust collar 12 and the cam member 10 are each provided with a series of radial holes 16 adapted to selectively receive the pins 17 on the tools or wrenches 18 which are provided with handles 19.

In the manipulation of the mandrel to expand the same the tools are first engaged with the members 10 and 12, being positioned so that the sleeve and shaft may be rotated relative to each other in direction to shift the clutch rollers to actuated position as shown in Fig. 2. The clutch rollers are shown in fully actuated position in this figure but it will be understood that they may be actuated to engage rolls or objects of different internal diameters. When securely engaged the clamping collar 14 is actuated to clamp the parts in their adjusted positions. In Fig. 1 the collar 14 is shown in its released position while in Fig. 4 it is shown adjusted to clamping position.

The embodiment of my invention illustrated in Figs. 5 to 8 inclusive is particularly desirable for the larger diameter mandrels. In this embodiment, the sleeve 20 corresponding to the sleeve 4 of the embodiment described is mounted on the shaft 1' in supporting engagement with the collar 7. This sleeve is provided with transverse slots 21, see Fig. 8, through which the pins 22 are disposed for securing the cam members 23 having cam surfaces 24 therein corresponding to the cam surfaces 2 of the embodiment shown in Fig. 3. These collars 23 are rotatably supported

on the sleeve as shown in Fig. 8 and by this arrangement I secure the same cooperating relation between the sleeve and the peripheral cam members on the shaft as in the embodiment described. The sleeve is provided with end flanges 25 and an intermediate flange 26 for supporting the clutch rollers 3'. These clutch rollers are supported for radial movement relative to the sleeve and the shaft by means of the journal blocks 27 which are supported in the radial slots 28 in the end flanges 25, pins 29 engaging the slots 30 retaining the journal blocks in the flanges. The rollers are positioned to coact with the cam surfaces on the collars as shown in Fig. 8 while the rollers are supported by the sleeves through its flanges 25 and 26. The flange 26 is provided with radial recesses 31, see Fig. 8. With this arrangement of parts, the relative rotative movement of the shaft and the sleeve actuates or retracts the clutch rollers the same as in the embodiment described. As stated, this embodiment is of special advantage in the larger diameter expanding mandrels. The same means are provided for clamping the parts in adjusted position.

25 The parts are capable of very easy and rapid manipulation both to expand the mandrel and to lock or secure it in its expanded or adjusted positions. Owing to the arrangement of the parts they may be very easily released.

30 I have illustrated and described my invention in an embodiment which I have found highly satisfactory. I have not attempted to illustrate or describe certain embodiments or adaptations which I contemplate as it is believed this disclosure will enable those skilled in the art to embody or adapt my improvements as may be desired.

Having thus described the invention what is claimed as new and desired to secure by Letters

40 Patent is:

1. An expandible mandrel comprising a shaft having a plurality of peripheral cam surfaces, a sleeve rotatably associated with said shaft and having a plurality of longitudinal slots therein and provided with a helical cam at one end, a thrust collar on said shaft coacting with the opposite end of said sleeve, knurled clutch rollers arranged in said slots in said sleeve to coact with said cam surfaces of said shaft, the cam surfaces being provided at one end thereof with seats receiving said rollers when the rollers are in released position, the seats being of such depth that the outer surfaces of the rollers are at substantially the periphery of the sleeve, a clamping collar rotatable on said shaft and having a helical cam coacting with the cam on the end of said sleeve, and a thrust collar on said shaft supporting said clamping collar, said sleeve, clamping collar and thrust collar being adapted to receive tools whereby the sleeve, the shaft and the clamping collar may be rotatively adjusted relative to each other.

2. An expandible mandrel comprising a shaft having a plurality of peripheral cam surfaces, a sleeve rotatably associated with said shaft and having a plurality of longitudinal slots therein and provided with a helical cam at one end, a thrust collar on said shaft coacting with the opposite end of said sleeve, knurled clutch rollers arranged in said slots in said sleeve to coact with said cam surfaces of said shaft, a clamping collar rotatable on said shaft and having a helical cam coacting with the cam on the end of said sleeve, and a thrust collar on said shaft supporting said clamping collar, said sleeve, clamping collar and thrust collar being adapted to receive tools whereby the sleeve, the shaft and the clamping collar may be rotatively adjusted relative to each other.

thrust collar being adapted to receive tools whereby the sleeve, the shaft and the clamping collar may be rotatively adjusted relative to each other.

3. An expandible mandrel comprising a shaft having a plurality of peripheral cam surfaces, a sleeve rotatably associated with said shaft and having a plurality of longitudinal slots therein and provided with an end thrust cam at one end, a thrust member on said shaft coacting with the opposite end of said sleeve, clutch rollers arranged in said slots in said sleeve to coact with said cam surfaces of said shaft, a clamping collar rotatable on said shaft and having an end thrust cam coacting with the end thrust cam on said sleeve, and a thrust member on said shaft supporting said clamping collar, said sleeve, clamping collar and thrust member being adapted to receive tools whereby the sleeve, the shaft and the clamping collar may be rotatively adjusted relative to each other.

4. An expandible mandrel comprising a shaft having a plurality of peripheral cam surfaces, a sleeve rotatably associated with said shaft and having a plurality of longitudinal slots therein and provided with an end thrust cam at one end, a thrust member on said shaft coacting with the opposite end of said sleeve, clutch rollers arranged in said slots in said sleeve to coact with said cam surfaces of said shaft, a clamping collar rotatable on said shaft and having an end thrust cam coacting with the end thrust cam on said sleeve, and a thrust member on said shaft supporting said clamping collar.

5. An expandible mandrel comprising a shaft having a plurality of peripheral cam surfaces, a sleeve rotatably associated with said shaft and having a plurality of longitudinal slots therein and provided with an end thrust cam at one end, a thrust member on said shaft coacting with the opposite end of said sleeve, clutch rollers arranged in said slots in said sleeve to coact with said cam surfaces of said shaft, the cam surfaces being provided at one end thereof with seats receiving said rollers when the rollers are in released position, the seats being of such depth that the outer surfaces of the rollers are at substantially the periphery of the sleeve, a clamping collar rotatable on said shaft and having an end thrust cam coacting with the end thrust cam on said sleeve, and a thrust member on said shaft supporting said clamping collar.

6. An expandible mandrel comprising a shaft carrying a plurality of peripheral cam surfaces, a sleeve rotatably associated with said shaft, clutch rollers mounted adjacent said sleeve for radial floating movement relative to the sleeve and in coacting relation to said cam surfaces on said shaft, an end thrust cam on one end of said sleeve, a thrust member on said shaft coacting with the opposite end of said sleeve, a clamping collar rotatable on said shaft and having an end thrust cam coacting with said end thrust cam on said sleeve, and a further thrust member on said shaft supporting said clamping collar, said sleeve, clamping collar and last named thrust member being adapted to receive tools whereby the sleeve, the shaft, and the clamping collar may be rotatively adjusted to each other.

7. An expandible mandrel comprising a shaft carrying a plurality of peripheral cam surfaces, a sleeve rotatably associated with said shaft, clutch rollers mounted adjacent said sleeve for radial floating movement relative to the sleeve and in coacting relation to said cam surfaces on said shaft, whereby relative movement of the

sleeve and shaft effects said radial floating movement, an end thrust member on said sleeve, a thrust member on said shaft restraining said sleeve from axial movement, a clamping member, 5 and means mounting said clamping member on said shaft for rotation only, said clamping member being operatively associated with said sleeve and thrust member to urge the sleeve axially against said shaft thrust member and effect 10 clamping of the sleeve to the shaft following relative rotation of the shaft and sleeve to position said clutch rollers radially.

8. An expansible mandrel comprising a shaft carrying a plurality of peripheral cam surfaces, 15 a sleeve rotatably associated with said shaft, clutch members mounted adjacent said sleeve for radial floating movement relative to the sleeve and in coaxing relation to said cam surfaces on said shaft, and means for effecting relative movement of said shaft and sleeve to shift said clutch members to actuated position and for clamping said shaft and sleeve in position to support the clutch members in actuated position comprising means for restraining said sleeve from endwise 20 movement, an end thrust member secured to said shaft, and coaxing cam members secured to said sleeve and rotatable on said shaft, respectively, said sleeve and shaft cam members being respectively rotatable relative to said end thrust member 25 and to one another to shift the clutch members and clamp the shaft and sleeve.

9. An expansible mandrel comprising a shaft carrying a plurality of peripheral cam surfaces, a sleeve rotatably associated with said shaft, clutch 30 rollers mounted adjacent said sleeve for radial floating movement relative to the sleeve and in supported coaxing relation to said cam surfaces, an end thrust member on said shaft coaxing with said sleeve, and coaxing end thrust clamping 35 members relatively rotatable on said shaft and

operatively associated with said shaft and sleeve for clamping said sleeve against said first named end thrust member.

10. An expansible mandrel comprising a shaft, a sleeve on said shaft, said shaft and sleeve being relatively rotatable, the sleeve being provided with a plurality of transverse slots, collars rotatably mounted on said sleeve and having peripheral cam surfaces, pins connecting said collars to said shaft disposed through said slots in said sleeve, 10 flanges on said sleeve having radial slots therein, clutch rollers provided with journal blocks radially slidable in said radial slots in said flanges and whereby they are supported for radial movement in cooperating relation to said peripheral cam 15 surfaces of said collars, an end thrust cam on said sleeve, a clamping member rotatable on said shaft to coat with said cam on said sleeve, a thrust collar on said shaft supporting said clamping member, and an end thrust member for said 20 sleeve carried by said shaft.

11. An expansible mandrel comprising a shaft, a sleeve on said shaft, said shaft and sleeve being relatively rotatable, the sleeve being provided with a plurality of transverse slots, collars rotatably mounted on said sleeve and having peripheral cam surfaces, pins connecting said collars to said shaft disposed through said slots in said sleeve, flanges on said sleeve having radial slots therein, clutch rollers provided with journal blocks radially slidable in said slots in said flanges and whereby they are supported for radial movement in cooperating relation to said peripheral cam surfaces of said collars, and coaxing end thrust clamping members rotatable on said shaft 30 and operatively associated with said shaft and sleeve for clamping said sleeve in its adjusted position relative to said shaft.
